CLAIM

The ornamental design for an electric driven compressor, as shown and described.

DESCRIPTION

FIG. 1 is a perspective view of the top, front and right side of an electric driven compressor showing our new design; FIG. 2 is a front view thereof; FIG. 3 is a rear view thereof; FIG. 4 is a left side view thereof; FIG. 5 is a right side view thereof; FIG. 6 is a top plan view thereof; and, FIG. 7 is a bottom view thereof.

The element shown in phantom lines do not form any part of the claimed design.
